DESIGN FOR AN ASH RECEIVER

Carl Richard Zettergren, New York, N. Y.

Application December 10, 1935, Serial No. 59,997

Term of patent 7 years

To all whom it may concern:

Be it known that I, Carl Richard Zettergren, a citizen of Sweden, residing at New York, in the county of New York and State of New York, have invented a new, original, and ornamental Design for Ash Receivers, of which the following is a specification, reference being had to the accompanying drawing, forming part thereof.

The figure is a perspective view of the ash receiver, showing my new design.

I claim:

The ornamental design for an ash receiver as shown.

CARL RICHARD ZETTERGREN.
